UNITED STATES PATENT OFFICE

92,690

DESIGN FOR AN OUTDOOR ELECTRICAL METER

Thomas A. Abbott, Marblehead, Mass., assignor
to General Electric Company, a corporation of
New York

Application July 21, 1933, Serial No. 48,785

Term of patent 14 years

To all whom it may concern:

Be it known that I, THOMAS A. ABBOTT, a citizen
of the United States, residing at Marblehead, in
the county of Essex, State of Massachusetts, have
invented a new, original, and ornamental Design
for an Outdoor Electrical Meter, of which the fol-
lowing is a specification, reference being had to
the accompanying drawing, forming a part there-
of.

In the drawing, Fig. 1 is a perspective view and
Fig. 2 is a front elevation of an outdoor electrical
meter showing my new design.

I claim:

The ornamental design for an outdoor elec-
trical meter, substantially as shown.

In witness whereof, I have hereunto set my
hand.

THOMAS A. ABBOTT.
